Primary Examiner—Stella Reid*Attorney, Agent, or Firm*—Oblon, Spivak, McClelland, Maier & Neustadt[57] **CLAIM**

The ornamental design for a baby bottle holder for a baby seat, as shown and described.

DESCRIPTION

FIG. 1 is a rear, top, three-quarters perspective view of a baby bottle holder for a baby seat showing my new design;

FIG. 2 is a right side elevational view thereof;

FIG. 3 top plan is a view thereof;

FIG. 4 is a front elevational view thereof; and,

FIG. 5 is a rear elevational view thereof.

The broken line showing of the baby seat and bottle in the figures is for illustrative purposes only and forms no part of the claimed design.

FIG. 2

FIG. 5

FIG. 4

FIG. 3
